UNITED STATES PATENT OFFICE.

GEORGE GEORGENSEN AND JOSEPH E. HENNEN, OF FOND DU LAC,
WISCONSIN.

ROLLER-SUPPORT FOR EDGEWISE-MOVABLE DOORS.

No. 845,631.

Specification of Letters Patent.

Patented Feb. 26, 1907.

Application filed August 7, 1906. Serial No. 329,591.

To all whom it may concern:

Be it known that we, GEORGE GEORGENSEN and JOSEPH E. HENNEN, citizens of the United States, residing at Fond du Lac, in the county of Fond du Lac and State of Wisconsin, have invented a new and useful Improvement in Roller-Supports for Edgewise-Movable Doors, of which the following is a specification.

10 This invention is a sliding-door-operating device particularly adapted for box - car doors.

It is characterized particularly by an operating-handle which is convenient as a handle for pulling the door open or closed and also for shifting the rollers on which the door slides, so that when the handle is in idle position the shoes at the lower edge of the car-door rest upon the track on which the door 20 slides, so that it will not accidentally slide open; but when the handle is operated the rollers are pressed down upon the track to lift the door and shift the weight thereof onto the rollers, so that the door will readily move.

25 A further feature of the invention is that the handle is located at the lower edge of the door in convenient position to be operated by the hands of a man on the ground or by the foot of a man on a platform, and by having the 30 rollers which support the weight of the door at the bottom thereof if there should be any resistance it would be near the operator. Thus if the door catch or the track become obstructed it can be readily remedied.

35 The invention is illustrated in the accompanying drawings, in which—

Figure 1 is a side elevation, partly broken away, of a car-door provided with the device with the door closed and the handle in inoperative position. Fig. 2 is a similar view 40 showing the parts in operation and the door partly open. Fig. 3 is an edge or end view of the door with adjacent parts of the car in section.

45 In the drawings the car-door is indicated at A, the floor at K, and the side of the car at L. On the side of the car, under the doorway, is a track F. The door has at its lower corners shoes H, which fit over the track and serve as retainers and also rest in contact upon the track to support and hold the door when the opener is inoperative.

E indicates a handle-rod or bail which extends along beside the lower edge of the door and has inturned ends, which are pivotally mounted in small boxes D, set in recesses in the door, so that the handle will swing down and out or up and in against the face of the door, as indicated in Fig. 3. The ends of the handle-rod are bent to extend outwardly through the boxes, and the projecting extremities beyond the same have cam-lugs d, which bear upon the top of the vertically-swinging roller-frames c, containing the rollers C, journaled therein. The frames c are hinged at B to angle-irons b, which are fixed to the bottom edge of the door and are preferably made to extend around the corner and part way up the edges of the door to strengthen the same, as indicated at b'. The plates G on front and back of the car-door form guides for the rollers and their frames and keep them in proper position.

In normal position the weight of the car-door bears the shoes H against the track and lifts the frames, the pressure of whose frames against the lugs d holds the handle swung up against the door. To open the door, the handle is swung down, causing the lugs to bear down on the roller-frames and lifting 80 the door, so that the shoes are raised from the track and the weight shifted onto the rollers, and the door can then be rolled upon the track with ease by pull or push on the handle or closed by similar operation.

85 The convenience of position and manipulation of the handle gives an ease of operation superior to ordinary devices and enables the door to be set in any desired position. The top of the door may be retained 90 and guided by any suitable or known devices.

We claim—

1. The combination with a sliding door and a track, of shoes on the door, which normally rest upon the track, rollers which travel on the track, frames hinged to the door and in which the rollers are journaled, and means to bear down upon the frames to shift the weight of the door from the shoes to the rollers.

100 2. The combination with a sliding door, of shoes at its lower edge, a track upon which the shoes normally rest and support the door, roller-frames hinged at one end to the lower

edge of the door, rollers which rest on the track and on which the frames are fulcrumed, and a handle pivoted on the door and bearing at its ends upon the frames, substantially as described.

3. The combination with a sliding door, of means to normally support the same, a track under the lower edge of the door, frames hinged at one end to the said lower edge, 10 rollers journaled in the frames and resting on the track, and a bent lever-handle extending

along beside the lower edge of the door and pivoted to the door, and having cam-lugs at its ends bearing upon the frames and adapted by pressure on the handle to lift the door and support the same on the rollers. 15

GEORGE GEORGENSEN.
JOSEPH E. HENNEN.
